UNITED STATES PATENT OFFICE.

CLINTON F. SHADLE, OF INDIANAPOLIS, INDIANA, ASSIGNOR, BY MESNE ASSIGNMENTS, TO INDIANA EQUIPMENT CORPORATION, OF INDIANAPOLIS, INDIANA, A CORPORATION OF INDIANA.

TRAIN-CONTROL VALVE CONSTRUCTION.

Application filed February 26, 1923. Serial No. 621,262.

To all whom it may concern:

Be it known that I, CLINTON F. SHADLE, a citizen of the United States, and a resident of Indianapolis, county of Marion, and State 5 of Indiana, have invented certain new and useful Train-Control Valve Constructions; and I do hereby declare that the following is a full, clear, and exact description thereof, reference being had to the accompanying 10 drawings, in which like numerals refer to like parts.

This invention relates to a train control system and particularly to a valve included in said system. The chief object of the 15 invention is to provide a valve construction of the character hereinafter described which is adapted to function in a complete train controlled system.

The chief feature of the invention consists 20 in providing for a fluid pressure conduit and exhaust construction controlled by a valve, which valve is electro-pneumatically controlled and which exhaust is of the dual character with one portion thereof electro-pneumatically controlled. Said electro-pneumatic controls are connected in parallel, 25 both electrically and pneumatically and so arranged mechanically that one of the controls is only operative when the other control 30 is operated.

A further feature of the invention consists in providing an additional fluid pressure conduit which exhausts through the before-mentioned exhaust construction, and 35 which is controlled by the before-mentioned exhaust controlling valve.

The full nature of this invention will be understood from the accompanying drawings and the following description and 40 claims.

In the drawings Fig. 1 is a top plan view 45 of a unitary valve construction and exhaust means associated therewith. Fig. 2 is a side elevational view of the same. Fig. 3 is a longitudinal sectional view taken on the line 3—3 of Fig. 1 and in the direction of the arrows. Fig. 4 is a longitudinal sectional view taken on the line 4—4 of Fig. 1 and taken in the direction of the arrows. Fig. 5 is a 50 longitudinal sectional view of a portion of the parts shown in Fig. 3 and illustrates said parts in a second position. Fig. 6 is a transverse sectional view taken on the line 6—6 of Fig. 1 and in the direction of

the arrows. Fig. 7 is a transverse sectional 55 view of an electro-pneumatic valve associated with the invention. Fig. 8 is a diagrammatic view of the electric and pneumatic connections embodied in the invention. 60

In Fig. 8 of the drawings there is diagrammatically illustrated the valve with its connections and the various controls. In said figure 10 indicates a valve body which contains a piston 11. The piston 11 is operated 65 by air pressure upon either face thereof, and said piston in its movement carries a valve member 12 to and fro. The valve member 12 is adapted to sever the connection between the pipe 13 and a pipe 14 70 (which herein includes one portion of the valve body 10) and close the pipe 13 and make a connection between the pipe 14 and a discharge pipe 15. The discharge conduit 75 15 discharges into an exhaust or pop valve 16. Said conduit 15 has a branch 17 which discharges into another pop valve 18, but the branch 17 is controlled by a valve 19 in turn controlled by an electro-pneumatic construction 20 having the supply line 21 and the circuit wire 22. A similar pneumatic control 23 is provided with the circuit wire 24 and a supply line 25. Herein the supply line 25 and the supply line 21 are connected in parallel and are supplied by a supply pipe 26. 80 Similarly the electro-pneumatic constructions are electrically connected together, having the common connection 27. A conduit 28 connects the electro-pneumatic control 20 with the valve 19. The electro-pneumatic control 23 is connected by the conduit 29 with the chamber 30 and said chamber is upon one side of the piston near the valve body 10. The other side of the piston 11 85 near the body 10 forms the connection between the conduits 13 and 14. In Fig. 8 the normal operative positions of the parts are illustrated and the full line arrows indicate the direction of air flow or pressure. The dotted line arrows indicate the direction of air flow when the valve operates.

The particular construction of the valve mechanism is shown in Figs. 3, 4 and 6. In the several figures the body is indicated generally by the numeral 10, and the same forms a chamber 31 adapted to receive a channeled plate 32 suitably secured therein by the bolts, as shown. The plate 32 slidably

supports the D-valve 12 carried by a slot 33 in the piston rod or stem 34. The D-valve is maintained in position upon the plate 32 by air pressure in the chamber 31 and a 5 spring 35 interposed between the slot 34 and said D-valve 12.

The body 10 is provided with an opening 36 which discharges into the chamber 31 and said opening 36 is adapted to receive the 10 conduit 13. An opening 37 is in communication with the chamber 31 through a registering opening 38 in the plate 32. The plate 32 also has an opening 39 which registers with a conduit 40 discharging into a chamber 41 formed in the body portion 10. When the D-valve 12 is in the position shown in Fig. 3 there is free communication from the conduit 13 to the conduit 14 through the chamber 31. When the D-valve 12, by means 15 of the stem 34, is moved into the position shown in Fig. 5, the conduit 13, although still in communication with the chamber 31, is disconnected or cut off from the conduit 14 for said openings 37 and 38, by means of 20 the D-valve 12, connect said conduit 14 with the chamber 41 through the registering openings 39 and 40.

The means for shifting or reciprocating the stem 34 is illustrated clearly in Fig. 3 30 and diagrammatically in Fig. 8. The body 10 carries a cylinder 30 which forms a chamber and in said chamber there is slidably mounted a piston 11 which is suitably secured to the stem 34 as illustrated. A cap 35 42 is associated with the cylinder 30 and the same forms an air tight chamber by suitable securing means, as illustrated. The cap 42 is provided with a port 43 which provides communication between the conduit 29, see 40 Figs. 3 and 8, and the chamber 30. Between the cover 42 and the end of the piston rod 34 there is interposed a cushioning spring 44.

The other end of the piston rod 34 is reduced as at 45 and said reduced end is slidably supported in a cap 36 having a threaded engagement with the opposite end of the body 10. Concentric with the reduced end of the stem 46 is a coil spring 47 and this spring assists in cushioning the stem in its 50 reciprocation toward the right, whereas the spring 44 assists in the cushioning of the stem in its movement toward the left. The end of the stem 45 is adapted to abut the end of the member 46, as shown clearly in Fig. 57, thereby limiting the movement toward the right. The chamber 31 is herein shown provided with an opening 48 closed by a cover plate 49 suitably secured thereto. A gasket 50 is interposed between said connection and 60 forms a fluid tight joint. This permits access to be had to the interior of the chamber 31.

With the foregoing construction it will be 65 understood that fluid under pressure, preferably air, is supplied through the conduit

29 to the chamber 30 and fluid under pressure is supplied by the conduit 13 to the chamber 31 and thence to the conduit 14. The chamber 29 is connected to a source of air pressure which is considerably higher, 70 and in practice the same is about 20 pounds per square inch than the air supplied by the conduit 13. It may be parenthetically stated that, when incorporated in a train control system, the conduit 13 comes from the main 75 feed pipe, or feed valve pipe in the braking system. The pressure air applied to the chamber 30 comes from the main reservoir. The pipe 14 connects the feed pipe to the engineer's automatic brake valve. In normal 80 position it may be assumed that the pressure in the chamber 30 exceeds the pressure in the chamber 31 by 20 pounds per square inch, and such excess of pressure causes the piston 11 to be positioned as shown in Fig. 85 3, which positions the D and slide valve 12 in the first or normal position, thereby permitting the conduit 13 and 14 to be connected or continuous. When the air is released in the chamber 30 or pressure is reduced therein, by reason of the operation of the electro-pneumatic control 23, the piston 90 11 moves to the left under the impetus of the pressure in the chamber 31 and the spring 46 and carries with it the slide valve 12. 95 When the slide valve 12 has been moved to its extreme position, as shown in Fig. 5, the conduit 13 does not communicate with the conduit 14. The conduit 14, by reason of 100 said D-valve 12 now communicates with the chamber 41 in the body of the valve and through means hereinafter to be described relieves the pressure in said pipe 14, and thus, as shown clearly by the dotted and full 105 lines in Fig. 8, the direction of the air flow in the pipe 14 is reversed from the normal flow.

As shown clearly in Figs. 1, 3 and 6, the means for supporting the valve body 10 includes the supporting plate portion 51 having the depending tongue 52. The flange or plate 51 also includes two other supporting portions 53 positioned above the tongue 52.

Upon the opposite side of the valve 51 and projecting laterally from the body portion is a portion providing the chamber 17. This is clearly shown in Figs. 4, 5 and 8. The chamber 17 communicates with the chamber 41 and suitably secured to said chamber 17 115 is an exhaust valve construction which, in Fig. 8, is indicated generally by the numeral 16. The details of the particular construction are old in the art. These valves 16 and 18 are known as the Westinghouse E-7 120 safety valve and are described in the "Instruction Pamphlet No. 5034 of 1914" entitled the "L N passenger car." The parts of 125 this valve are the body 54, cap nut 55, valve 56, stem 57, spring 58, regulating nut 59 130

and locking ring 60. When the pressure in the cavity 61 is sufficient to overcome the pressure exerted by the tension of the spring 58, the valve 56 is raised from its seat, which 5 upward movement closes the end of the port 62 in the valve bushing and opens the ports 63 permitting air to flow from the conduit 61 through the chamber 64 and port 63 to the atmosphere. As the pressure below the 10 valve decreases, the tension of the spring 58 forces the valve 56 downward, which restricts the opening through the port 63 to the atmosphere and opens the upper end of the port 62 to the spring chamber 65. Al- 15 though the spring chamber 65 is open to the atmosphere at all times through the ports 66, these ports are sufficiently small to restrict the exhaust so that the pressure builds up very rapidly in the spring chamber 65 and 20 assists the spring 58 in forcing quickly the valve 56 to its seat. The adjustment of this valve construction is that described in the before mentioned pamphlet and may be ob- 25 served from Fig. 4. Thus, within certain limits the closing pressure can be regulated as well as the pressure at which the valve will open, and moreover this valve opens and closes with a quick action, permitting air to escape to the atmosphere quickly when open, 30 and causing the valve to seat promptly and firmly when closed.

As shown clearly in Fig. 4, communication between the chamber 61 and the chamber 17, is had through a suitable filter screen 67. 35 This screen likewise is old in the art. The chamber 17 discharges into the standard pop valve 18, shown in Fig. 8 and in Fig. 4. The pop valve 18 is substantially similar to the pop valve 16 described in detail herein- 40 before, and the same action is secured therefrom. However, the chamber 17 communi- cates with the auxiliary chamber 117 carrying the pop valve 18 through the valve construction indicated generally by the numeral 45 19 in Fig. 8. The body 10, or rather the lateral projection therefrom, is provided with a pair of registering apertures 76 and 77. The aperture 77 is threaded to receive a hollow plug 78, which plug forms a tapered 50 seat 79 and communicating with the hollow portion of said plug is a plurality of trans- versely extending ports 80. A frusto-conical valve 81 supported by a stem 82, in turn sup- 55 ported by a piston construction 83. The pis- ton construction 83 is supported upon a coil spring 84 interposed between it and a por- 60 tion of the casing 85. The top of the cylin- der 85 is closed by a cylinder head 86 aper- 65 tured to receive the conduit 28. Air under pressure is admitted to the cylinder 85 through the conduit 28 and normally main- 70 tains the conical valve 81 upon its seat. When the air is exhausted from the conduit 28, the piston 82 under the action of the 75 spring 84 and pressure in chamber 17 raises

from its seat and the air from the chamber 17 discharges through the ports 80 and into the chamber 117 and thence to the pop valve 18, whence it escapes to the atmosphere with a popping action, as hereinbefore described. 70 The conduit 28 is electro-pneumatically con- 75 trolled by the means indicated generally at 20 and is supplied with air under pressure from the supply pipe 26 through the branch 21.

Since the electro-pneumatic controls 20 and 23 are substantially similar, a descrip- 80 tion of one will suffice for an understanding of them both, and herein such a construction is illustrated in Fig. 7 and this is substan- 85 tially a standard construction and is illus- trated and described in the Railway Elec- 90 trical Engineer, page 313, of September 19, 1919. It may be assumed that we are de- 95 scribing this construction with reference to the electro-pneumatic control 23 and herein the body portion is indicated by the numeral 23. The body portion is connected to the supply pipe 25 and to the outlet 24. The body 23 is provided with two channels or 100 conduits 87 and 88 which communicate re- 105 spectively with the conduits 25 and 29. The conduit 87 discharges into a chamber 89 and the conduit 88 communicates with a chamber 90. A plug 91 is provided with a 110 channel 92 and includes a valve seat 93, closed by a conical valve 94 having the stem 95 which extends through the conduit 92. The valve 94 carries a spring seat 96 with 115 which is associated a spring 97 retained in 120 position by a spring retainer and plug closure 98. The spring 97 tends to maintain the valve 96 in the closed position. Com- 125 municating with the chamber 95, and by means of the plug 91, is a conduit 99 con- 130 trolled by a valve 100 carried by the stem 101. The conduit 99 discharges into the chamber 102, which has free access to the 135 atmosphere at 103. The valve construction hereinbefore described constitutes a differ- 140 ential valve and the normal position thereof is to provide communication between the conduits 29 and 25, but when operated to 145 close or sever said connection and permit the air in the conduit 29 to discharge 150 through the port 103 and to the atmosphere.

The means for operating the valve is as follows: A core 104 is threaded into the body portion 23 and has a channel 105 ex- 155 tends longitudinally therethrough. Said channel is adapted to slidably support the valve stem 101. Concentric with the core 104 and supported by the body portion 23 is an electro-magnet 106 which comprises a solenoid having the terminals 107. Said 160 magnet is secured in position and retained therein by the locking nut 108 which en- 165 gages the core 104. The valve stem 101 which passes through the channel 106 of the core 104 carries an armature 109. Said 170

armature is slidably supported in a cover 110 which, together with the body portion 111, integral with the body portion 23, forms a closed housing for the electro-magnet construction. The closure 112 slidably supports an extension 113 of the valve stem 101. When the electro-magnet is energized, the same operates the valve through the armature and maintains communication between the pipes 25 and 29. Said valve operation has been previously described. In order to prevent rotational movement of the valve, by reason of the rotational movement of the stem, a pin 114 is interposed in the path of the stem 101 and, while permitting longitudinal movement, prevents rotational movement thereof. Deenergization of the electro-magnet permits the air in the pipe 29 to exhaust through the port 103.

Reference will now be had to Figs. 3, 4, 5, and 8. In said figures there is illustrated a fluid pressure pipe 125 which is suitably connected to a portion of the standard braking system. The body portion of the valve is provided with a conduit 124 which communicates with the conduit 125 and also with an aperture or projection 123 in the plate 32. The D-valve 12 has a pair of openings 120 and 122 which communicate with each other through the channel 121. As shown clearly in Fig. 3, when the valve is in the normal position the conduit 125 is blank or cut off, but when said valve is moved to the other position, as shown in Fig. 5, the conduit 125 exhausts or discharges through the registering openings 39 and 40 to the chamber 41 which, as previously described, exhausts through the pop valve 16 or the pop valves 16 and 18, depending upon certain conditions.

The invention claimed is:

1. The combination of a fluid pressure conduit, an exhaust therefor, a second exhaust connected therewith, a single valve means controlling both exhaust connections, another valve interposed in said exhaust connection for controlling one of said exhausts, and electrical means for controlling said second valve.
2. The combination of a fluid pressure conduit, an exhaust therefor, a second exhaust connected therewith, a single valve means controlling both exhaust connections, another valve interposed in said exhaust connection for controlling one of said exhausts, and pneumatic means for controlling said second valve.
3. The combination of a fluid pressure conduit, an exhaust therefor, a second exhaust connected therewith, a single valve means controlling both exhaust connections, another valve interposed in said exhaust connection for controlling one of said exhausts, and electro-pneumatic means for controlling said second valve.

4. The combination of a fluid pressure conduit, an exhaust therefor, a second exhaust connected therewith, a single valve means controlling both exhaust connections, another valve interposed in said exhaust connection for controlling one of said exhausts, a balanced control for said second valve, and means for disturbing said balance.

5. A device of the character described in claim 4 wherein the disturbing means is electrical in character.

6. A device of the character described in claim 1 provided with an electrical control for said first mentioned valve.

7. A device of the character described in claim 1 provided with a pneumatic control for said first mentioned valve.

8. A device of the character described in claim 1 provided with an electro-pneumatic control for said first mentioned valve.

9. A device of the character described in claim 2 provided with an electric control for said first mentioned valve.

10. A device of the character described in claim 2 provided with a pneumatic control for said first mentioned valve.

11. A device of the character described in claim 2 provided with an electro-pneumatic control for said first mentioned valve.

12. A device of the character described in claim 3 provided with an electric control for said first valve.

13. A device of the character described in claim 3 provided with a pneumatic control for said first valve.

14. A device of the character described in claim 3 provided with an electro-pneumatic control for said first valve.

15. A device of the character described in claim 4 provided with an electric control for said first valve.

16. A device of the character described in claim 4 provided with a pneumatic control for said first valve.

17. A device of the character described in claim 4 provided with an electro-pneumatic control for said first valve.

18. A device of the character described in claim 5 provided with an electric control for said first valve.

19. A device of the character described in claim 5 provided with a pneumatic control for said first valve.

20. A device of the character described in claim 5 provided with an electro-pneumatic control.

21. The combination of a fluid pressure conduit, an exhaust therefor, a second exhaust connected therewith, valve means controlling both exhausts, another valve interposed in said exhaust connection for controlling one of said exhausts, and a pair of electrical controls connected together for controlling both valves in predetermined relation.

22. The combination of a fluid pressure conduit, an exhaust therefor, a second exhaust connected therewith, valve means controlling both exhausts, another valve interposed in said exhaust connection for controlling one of said exhausts, and a pair of pneumatic controls connected together for controlling both valves in predetermined relation.
- 10 23. The combination of a fluid pressure conduit, an exhaust therefor, a second exhaust connected therewith, valve means controlling both exhausts, another valve interposed in said exhaust connection for controlling one of said exhausts, a pair of pneumatic controls for said valves and connected in parallel, and an electric control for each pneumatic control.
- 15 24. The combination of a fluid pressure conduit, an exhaust therefor, a second exhaust connected therewith, valve means controlling both exhausts, another valve interposed in said exhaust connection for controlling one of said exhausts, a pneumatic control for each valve, and a pair of electric controls for said pneumatic controls and connected in parallel for predetermined operation.
- 20 25. In a device of the character described in claim 23 a parallel electrical connection 30 for said electrical controls.
- 25 26. The combination with a plurality of fluid pressure conduits, an exhaust therefor, and a single valve for connecting said conduits to said exhaust. 35
27. The combination with a normally open fluid pressure line, another and normally closed fluid pressure line, an exhaust, and valve means interposed between said first mentioned fluid pressure line to connect the 40 same to the exhaust and connect the other pressure line to said exhaust.
28. The combination with a pair of normally communicating pressure lines, a third pressure line, an exhaust, and a valve for 45 severing the communication between said pair of lines and connecting one of said connecting lines to the exhaust and the third pressure line to said exhaust.

In witness whereof, I have hereunto affixed my signature.

CLINTON F. SHADLE.
